(57) **CLAIM**

The ornamental design for a spray dispensing container, as shown and described.

DESCRIPTION

FIG. 1 is a top, front perspective view of a spray dispensing container showing our new design in a closed configuration; FIG. 2 is a bottom, rear perspective view thereof; FIG. 3 is a side view thereof;

FIG. 4 is a side view thereof, wherein the container is rotated around a vertical axis 180° in relation to the view illustrated in FIG. 3;

FIG. 5 is a rear view thereof;

FIG. 6 is a front view thereof;

FIG. 7 is a top plan view thereof;

FIG. 8 is a bottom plan view thereof;

FIG. 9 is a top, front perspective view showing our new design in an open configuration;

FIG. 10 is a bottom, rear perspective view of FIG. 9;

FIG. 11 is a side view of FIG. 9; and,

FIG. 12 is a front view of FIG. 9.
